FENDER FOR AN AUTOMOBILE

Carl H. Renner, Detroit, Mich., assignor to General Motors Corporation, Detroit, Mich., a corporation of Delaware

Application December 4, 1953, Serial No. 27,932

Term of patent 7 years

(Cl. D14—6)

To all whom it may concern:

Be it known that I, Carl H. Renner, a citizen of the United States, being a resident of Detroit, Michigan, have invented a new, original, and ornamental Design for a Fender for an Automobile, of which the following is a specification, reference being made to the accompanying drawing, forming a part thereof.

In the drawing:

Fig. 1 is a side elevational view of a fender for an automobile incorporating my new design;

Fig. 2 is a longitudinal section through the fender of Fig. 1, taken along the line 2—2 of Fig. 1;

Fig. 3 is a transverse vertical section through the fender of Fig. 1, being taken along the line 3—3 of Fig. 1.

The fragmentary dotted line disclosure of an automobile is shown only for the purpose of illustration.

I claim:

The ornamental design for a fender for an automobile, substantially as shown and described.
